XF D 12,514

DESIGN FOR A NEWEL-POST.

Design No. 12,514, dated October 11, 1881.

UNITED STATES PATENT OFFICE.

JAMES I. HEALEY, OF BROOKLYN, NEW YORK.

DESIGN FOR A NEWEL-POST.

SPECIFICATION forming part of Design No. 12,514, dated October 11, 1881.

Application filed September 5, 1881. Term of patent 3½ years.

To all whom it may concern:

Be it known that I, JAMES I. HEALEY, a citizen of the United States, residing at Brooklyn, in the county of Kings and State of New York, have invented and produced a new and original Design for Newel-Posts, of which the following is a specification, reference being had to the accompanying photograph, forming part thereof, and which illustrates a perspective view of the post.

The object of the invention is to provide a new and original design for a newel-post, consisting of an ornamental base, sides, and head or top supporting a vase or urn, as shown in the accompanying photograph, and hereinafter described.

In the photograph, A represents the base of the post, consisting of the flat-faced moldings *a b* and the round-faced molding *c*, and above this latter molding is an ornamental bead, *d*. The sides or panels of the post have a circular flower, *e*, and around said flower are arranged four scrolls, *f*, and at each corner of the sides or panels are spiral columns *g*. Above the sides or panels of the post is a fluted surface, *h*, located between two ornamental beads, *i k*, and above this is the ornamental head *B*, which has upon each side a V-shaped pendant,

l, with a flower, *m*. This ornamental head *B* supports a covered vase or urn, *C*, consisting of an ornamental base, *n*, flutes *o*, and finial *p*.

Having now fully described my invention, what I claim as new, and desire to secure by Letters Patent, is—

1. A design for the top of a newel post, consisting of the head *B*, with V-shaped pendants *l*, flowers *m*, fluted surface *h*, and beads *i k*, said head *B* supporting an urn or vase, *C*, substantially as shown and described. 35

2. A design for the sides or panels of a newel-post, consisting of the circular flower *e*, scrolls *f*, and spiral columns *g*, substantially as shown and described. 40

3. A design for newel-posts, consisting of the base *A*, sides or panels having the circular flower *e*, scrolls *f*, and spiral columns *g*, the fluted surface *h*, beads *i k*, head *B*, with V-shaped pendants *l*, flowers *m*, and the vase or urn *C*, substantially as shown and described. 45

In testimony that I claim the foregoing as my own I herewith affix my signature in the presence of two witnesses.

JAMES I. HEALEY.

Witnesses:

WASHINGTON ROBERTS,
J. F. HEALEY.
